UNITED STATES PATENT OFFICE.

JOHN HENRY GIBBS, OF WEST ORANGE, NEW JERSEY.

COLLAPSIBLE-TUBE HOLDER.

1,374,845.

Specification of Letters Patent. Patented Apr. 12, 1921.

Application filed September 30, 1919. Serial No. 327,368.

To all whom it may concern:

Be it known that I, JOHN H. GIBBS, a citizen of the United States, and a resident of West Orange, in the county of Essex and 5 State of New Jersey, have invented a new and useful Collapsible-Tube Holder, of which the following is a full, clear, and exact description.

This invention relates to tube holding devices and particularly to holding devices for collapsible tubes. The object of the invention is to provide a holder which will act in the double capacity of a holder and means for collapsing the tube to any desired extent. 10 Another object of the invention is to provide a holder wherein means are provided for collapsing a tube, the holder being constructed in such a manner as to be readily applied to a wall or other support at a point 15 of ready access.

In the accompanying drawing:

Figure 1 is a front elevation of a holder disclosing an embodiment of the invention, the same being shown in connection with a 25 collapsible tube arranged in position ready for collapsing.

Fig. 2 is a section through Fig. 1 on line 2—2.

Fig. 3 is a horizontal section through Fig. 30 1 on line 3—3.

Referring to the accompanying drawing by numerals, 1 indicates a support of any desired kind, as for instance the wall of a bath-room and 2 the holder in its entirety, 35 said holder carrying the tube 3 which is of any usual construction, the same having a cap 4 at one end and a closed section 5 at the opposite end, said closed section being flat in the usual manner now in common 40 practice. It will, of course, be understood that the holder 2 may be used in connection with collapsible tubes carrying tooth-paste or with collapsible tubes containing any other material. The holder 2 is provided 45 with a central section 6 on which the tube 3 rests, said section having upstanding lugs 7 and 8 which are preferably integral with the respective plate sections 9 and 10, which 50 plate sections merge into ends 11 and 12 which receive fastening means, as for instance screws. The plate section 9 is provided with upstanding ears 13 and 14, said

ears having apertures 15 therein for accommodating the winding and collapsing key 16. This key is provided with a body 55 17 having a slot 18 therein with a reduced upset end 19 and a head 20.

In operation the closed end 5 is passed through the slot 18 and the key turned over to substantially the position shown in Figs. 60 1 and 2. The device is then in position for use. Whenever cap 4 is removed the key 16 may be rotated and the tube collapsed as often as desired, while the contents will be discharged at a proportionate rate. Where 65 the tube 3 carries tooth-paste for instance, the cap 4 may be removed and the brush held beneath the discharge opening of the tube by one hand while the opposite end 70 operates the winding key for forcing the desired quantity of paste on to the brush. This may be done as often as desired without laying the brush down and without laying the tube down in a more or less unsanitary place. By this construction and arrangement the contents of the tube does not 75 touch anything until it comes in contact with the brush or other device placed beneath the tube for receiving the same. If vaseline or in fact if any other material is 80 placed in the tube the discharge thereof is in the same sanitary manner.

As shown in Fig. 2 the lug 7 is positioned sufficiently near the key to cause the proper 85 collapsing of the entire tube so that all of the contents may be secured before the discharge end is wrapped on the key.

What I claim is:

1. A holder for collapsible tubes comprising a body formed with a central tube carrying portion, depressed end sections adapted to receive securing means, a pair of upstanding ears arranged on one of said end sections, and a rotatable collapsing key mounted in said ears and adapted to engage 95 the end of the tube, said tube being arranged on the central tube carrying portion, said key being arranged on a vertical line spaced horizontally away from said tube carrying section by a distance equal to approximately half the thickness of the tube 100 so that upon the rotation of the key, the tube will be collapsed and pressed against said tube carrying portion.

2. A holder for collapsible tubes comprising a body formed from a single piece of metal bent for producing a centrally raised section, two depressed end sections, and a 5 pair of upstanding ears on one of the end sections, said ears projecting beyond said centrally raised section, each of said ears hav-

ing an aperture therein and a rotatable slotted key arranged in said aperture for receiving the end of a tube positioned on 10 said raised portion whereby said tube may be wound thereon and thereby collapsed as the key is rotated.

JOHN HENRY GIBBS.
